UNITED STATES PATENT OFFICE.

EUGENE C. STACY, OF TIFFIN, OHIO.

DESIGN FOR A LINK.

52,589.

Specification for Design.

Patented Oct. 15, 1918.

Application filed May 25, 1917. Serial No. 171,036. Term of patent 14 years.

To all whom it may concern:

Be it known that I, EUGENE C. STACY, a citizen of the United States, residing at Tiffin, in the county of Seneca and State of Ohio, have invented a new, original, and ornamental Design for a Link, of which the following is a specification, reference being had to the accompanying drawings, forming part thereof.

Figure 1, is a side view and Fig. 2, is an edge view.

I claim:

The ornamental design for a link, as shown.

EUGENE C. STACY.
